NOZZLE FOR SUCTION CLEANER OR THE LIKE

Albert B. Campbell, Glen Ellyn, Ill., assignor to Campbell Products Company, Bensenville, Ill., a corporation of Illinois

Filed Nov. 9, 1961, Ser. No. 67,446

Term of patent 14 years

(Cl. D9—2)

FIG. 1 is a front perspective view of a nozzle for a suction cleaner or the like showing my new design, the portions of a suction cleaner shown in broken lines being for illustrative purposes only;

FIG. 2 is a top plan view thereof;

FIG. 3 is a front view thereof; and

FIG. 4 is a side view thereof.

What is claimed is:

The ornamental design for a nozzle for suction cleaner or the like, as shown and described.
